UNITED STATES PATENT OFFICE.

HARRY L. MORAWETZ, OF MILWAUKEE, WISCONSIN.

CONTAINER-STRAP-SEALING DEVICE.

1,361,890.

Specification of Letters Patent. Patented Dec. 14, 1920.

Application filed November 19, 1919. Serial No. 339,023.

To all whom it may concern:

Be it known that I, HARRY L. MORAWETZ, a citizen of the United States, and resident of Milwaukee, in the county of Milwaukee and State of Wisconsin, have invented new and useful Improvements in Container-Strap-Sealing Devices, of which the following is a description, reference being had to the accompanying drawings, which are a part of this specification.

This invention relates to improvements in container strap sealing devices.

In shipping boxes or packages and more particularly paste board or fiber containers, it is now quite common to bind the boxes or containers with metal straps to eliminate the use of nails, screws or other cover fastening means. In use the metal straps are extended around the sides and ends of the containers and the end portions of each strap are overlapped and crimped together in connection with metal seals which prevent the separation of the overlapped ends. In fastening the strap ends the straps are drawn as tightly as possible around the container but during shipment the containers are piled upon one another and, more particularly in paste board or fiber containers, the covers are forced into more intimate contact with the body portions or the contents may be more closely forced together with the result that the individual straps become loosened or slack and may be easily slid edgewise off the containers and the contents of the containers be surreptitiously removed by unscrupulous persons and the straps be replaced. As thus restrapped the containers will not indicate that they have been pilfered and they will be received by the consignee from the transportation company as in good order. It may be some time after receipt of shipment that the container is opened and the loss discovered and it is then almost impossible to trace the matter or hold the transportation company responsible for the loss. Losses of this kind are quite common and are a source of endless trouble and expense.

It is one of the objects of the present invention to overcome the before-mentioned objectionable features and provide a container strap sealing device constructed to prevent the removal of the metal binding

straps without cutting the straps or the seals so that if a container has been tampered with, it will be easily apparent from an exterior inspection thereof.

A further object of the invention is to provide a container strap sealing device in which the crossed metal binding straps are connected together in such a manner as to prevent said straps from being moved edge-wise from the container.

A further object of the invention is to provide a container strap sealing device which is adapted to be used in connection with the ordinary strap end sealing means now in use in placing the metal straps around containers.

A further object of the invention is to provide a container strap sealing means which is of simple construction, is strong and durable and is well adapted for the purpose described.

With the above and other objects in view, the invention consists of the improved container strap sealing device and its parts and combinations as set forth in the claims and all equivalents thereof.

In the accompanying drawing in which the same reference characters indicate the same parts in all of the views:

Figure 1 is a perspective view of a container having metal straps provided with the improved sealing device;

Fig. 2 is a perspective view on a larger scale of two crossed metal straps connected together by the improved sealing device;

Fig. 3 is a top view of overlapped strap end portions showing manner of connecting and sealing them together.

Fig. 4 is a transverse sectional view thereof taken on line 4-4 of Fig. 3;

Fig. 5 is a transverse sectional view taken on line 5-5 of Fig. 2;

Fig. 6 is a perspective view of a modified form of sealing device shown mounted on two crossed straps; and

Fig. 7 is a similar view of another modified form.

Referring to the drawing, the numeral 8 indicates a rectangular container formed of any desirable material which is bound by two metal straps 9 and 10 extending around the container at right angles to each other.

The ends 11 of the straps are overlapped

and partly inclosed by securing means 12 of channel shape in cross section which are crimped edgewise as indicated by the numeral 13 to lock the parts together. The parts thus far described are of ordinary construction and now in use and on the market. As thus constructed the straps become slack when the containers are subjected to pressure and may be easily slipped edgewise off the container and as easily replaced without any exterior indication thereof.

The right angularly extending metal straps 9 and 10 necessarily cross each other and at the point of crossing or intersection 15 a sealing lock 14 is mounted on the straps to prevent the edgewise movement of the straps. The sealing lock in the preferred form comprises a body portion 15 of rectangular shape having flanges 16 extending 20 at right angles from its four edge portions which are provided with elongated slots or eyes 17. Each strap extends through two of the slots as clearly shown in the drawing and the portions of the straps adjacent the 25 side edges of the body portion 15 are crimped edgewise as indicated by the numeral 18 by the same tool which is used for crimping the overlapped strap ends before-mentioned. The edge crimping flanges or 30 shoulders the opposite side edge portions 18' of the straps at right angles to the sides of the strap and to such an extent as to prevent said portions from passing through the slots of the lock seal and straps are thus locked in 35 position on the container; as neither strap can be moved edgewise without exerting a lengthwise pull on the other strap extending at right angles thereto and said other strap cannot be moved endwise due to the angular 40 corner edge bends or shoulders 19 of said strap.

In the modified form shown in Fig. 6, the body portion 15' is of circular shape and is provided with an annular flange 16' having 45 elongated slots 17' formed therein. These slots are positioned in pairs opposite each other to receive the strap portions in the same manner described in the preferred form.

50 In the modified form shown in Fig. 7, the sealing lock comprises an elongated body portion 20 having an elongated slot 21 formed therein through which both straps 9 and 10 pass at the point of intersection of 55 said straps. The portion 20' of the lock which extends beneath the intersecting strap portions is offset laterally approximately the thickness of the two straps to permit said lock to rest flatwise against the strap portions. The portions of the straps adjacent 60 the lock are crimped edgewise in the same manner before described.

In use the straps are placed around the container in the usual manner and at the 65 point of crossing or intersection are slipped

through the elongated slot or slots and the ends of the straps are then overlapped and drawn tight and then crimped in connection with a securing means. When the strap ends are thus connected the crimping tool 70 is then used to crimp the edge portions of the straps adjacent the seal lock and the straps cannot be removed from the container without cutting the parts and thus giving visible notice of the pilfering. While 75 the edge crimping means has been shown and described for locking the locking seal in position on the straps it is to be understood that the straps may be otherwise crimped or shouldered or bent to prevent movement of 80 the locking seal with relation to the straps.

From the foregoing description it will be seen that the container strap sealing device is of very simple construction and is well adapted for the purpose described.

85 What I claim as my invention is:

1. A container having straps crossed medially of their length and formed of resilient bendable material crimped to form angled portions adjacent to but spaced from the point of intersection, and means engaging the straps at the point of intersection and between the angled portions for preventing relative movement thereof.

2. A container having straps crossed medially of their length and formed of resilient bendable material crimped to form angled portions adjacent to but spaced from the point of intersection, and means at the point of intersection and between the angled portions of the straps and through which the straps extend for preventing lateral edgewise movement of the straps on the container.

3. A container having crossed straps 105 thereon formed of bendable material angled adjacent the point of intersection, a locking means therefor consisting of a slotted member at the point of intersection of the straps and through which the straps extend at 110 right angles to each other, the angled portions of said straps positioned on opposite side edge portions of the locking means to prevent movement of the straps through the slotted member or on the container.

4. A container having crossed straps thereon formed of bendable material, a locking means therefor having a plurality of elongated slots through which the straps at the point of intersection extend, the said 120 straps on each side edge of the locking means being crimped to prevent movement of the straps through the slots or on the container.

5. A container having crossed straps thereon formed of bendable material, a locking means therefor comprising a body portion having a flanged portion provided with elongated slots through which the straps at the point of intersection extend at right angles to each other, the said straps adjacent 125 130

the locking means being crimped to prevent movement of the straps through the slots or on the container.

6. A container having crossed bendable metal straps thereon, a locking means therefore comprising a body portion of rectangular shape having an angularly extending flange on each edge which is provided with elongated slots through which the straps extend 10 at right angles to each other, each strap on each side edge of the locking means being flanged at an angle transversely of the strap

to form shoulders to prevent movement of the straps through the slots and with relation to each other.

7. A locking means for shouldered crossed straps on a container consisting of a bendable sheet metal body portion having four flanged portions bent at an angle from the body portion and provided with elongated 20 openings for receiving therethrough crossed shouldered straps.

In testimony whereof I affix my signature.
HARRY L. MORAWETZ.
